UNITED STATES PATENT OFFICE.

ARTHUR JOSEPH LA FAY, OF TORONTO, ONTARIO, CANADA.

HEATING APPARATUS.

1,349,617.

Specification of Letters Patent. Patented Aug. 17, 1920.

Application filed October 25, 1919, Serial No. 333,152.

To all whom it may concern:

Be it known that I, Arthur Joseph La Fay, a resident of the city of Toronto, in the county of York, Province of Ontario, Canada, have invented certain new and useful Improvements in Heating Apparatus, of which the following is a specification.

This invention relates to means for increasing the efficiency of the well known fluid heating furnace commonly employed in the heating of buildings. The general principle involved in the construction of the apparatus is to jacket the outer surface or casing of the heater with the hot products of combustion before the latter are led to the smoke stack or chimney. Over this surface the hot products of combustion may be led in a zigzag course by means of longitudinal baffles which divide the space between the furnace walls or casing and an outer casing into longitudinal flues, dampers being provided to permit of direct draft whenever desired.

In my co-pending application No. 284962 filed March 25th, 1919, the invention was applied to a horizontal furnace with vertical sections. In the present invention I illustrate the device as applied to an ordinary vertical horizontal-section hot water and steam boiler.

The apparatus is constructed in detail as hereinafter more specifically described and as illustrated in the accompanying drawings in which—

Figure 1 is a front elevation showing a vertical furnace provided with my improvements;

Fig. 2 a side elevation of the same, partly in section; and

Fig. 3 a horizontal section on the line *a—b* in Fig. 2.

In the drawings like numerals of reference indicate corresponding parts in the different figures.

1 is a vertical hot water or steam boiler of any ordinary sectional type, though the invention is, of course, applicable to other constructions of vertical furnace.

In this furnace 2 is the smoke exit and 3 the furnace casing. The furnace is surrounded by an external casing 4 which is preferably made of some suitable heat insulating material or of metal lined with such material, and which is made completely air tight. This casing is so arranged that the front of the furnace, with the fuel, ash-

pit and clean-out doors, is exposed as shown particularly in Figs. 1 and 3. This casing extends above the top of the furnace as shown more particularly in Fig. 2. The space between the furnace casing and the external casing is divided into a plurality of longitudinal communicating flues by means of a plurality of baffles 5. In the preferred arrangement three such baffles are shown at each side of the furnace. Passages for the products of combustion are formed alternately at opposite ends of these baffles as shown. The products of combustion from the smoke exit 2 are prevented from passing directly to the smoke outlet 6 leading from the outer casing by means of the horizontal baffles 7 at the top of the furnace and the walls of the flue 8, which extend between the top of the furnace casing and the top of the external casing. In this flue is located the damper 9. When this damper is closed as shown in Figs. 2 and 3, the products of combustion must pass down the longitudinal flues at each side of the furnace at the front, thence through each of the other longitudinal flues in the series until they reach the longitudinal flue at the back with which the smoke outlet 6 directly communicates.

The smoke outlet 6 may be wider at the top or the side as indicated in Fig. 2.

In case it is found that it is not desirable to give the hot products of combustion such a long course over the external surface of the furnace casing, I provide a damper 10 in the front baffle 5 at each side. When these dampers are open the products of combustion may pass at each side directly to the next to last longitudinal flue toward the back of the furnace, thence down this flue and up the flue immediately at the back of the smoke outlet. When the damper 9 is thrown down to the horizontal position, the products of combustion from the smoke exit 2 may pass directly to the smoke outlet 6 giving the benefit of direct draft when the fire is being started or at such other times as very strong draft is needed.

Clean-out doors 11 are provided in the external casing wherever needed.

I find that there are certain advantages in introducing heated air into the products of combustion under certain conditions. I therefore provide the pipes 12 which are led to the space between the two casings near the front and are carried up to the

top where the air is discharged to mix with the products of combustion. The lower end of each pipe ~~may be provided with a~~ ^{controlling} valve. The water connections of the heater are shown at 14-15, but of course any ordinary arrangement may be adapted.

As a matter of fact, the external casing and baffles may be applied to any type of vertical boiler, the details being varied according to the specific construction of the furnace.

I find that with the construction shown I am enabled to secure greatly increased efficiency in the operation of the furnace for heating fluids while maintaining under all circumstances an adequate draft.

What I claim as my invention is:—

1. The combination with a fluid heating furnace of the vertical type provided with internal flues for the products of combustion and spaces for the fluid to be heated externally bounded by the casing of the furnace and surrounding the internal flues, fuel and ashpit doors at one side and a single smoke exit in the top, of an external casing spaced from the sides of the casing but leaving the front of the casing with the fuel and ashpit doors exposed; a smoke outlet at the top of the external casing; depending baffles, one at each side of the furnace, dividing the space between the casings into a plurality of vertical flues; vertical walls, extending between the top of the furnace casing and the top of the external casing, and from the sides of the smoke exit of the furnace to the wall of the said casing, said walls forming a flue, the smoke exit of the furnace, the smoke outlet of the external casing and the space between the two casings all communicating with said

flue; a damper in said flue adapted to cut off direct communication between the said smoke exit and the said smoke outlet; and horizontal baffles adapted to direct products of combustion from the smoke exit to the space between the two casings at the side of the vertical baffles remote from the smoke outlet of the external casing. 45

2. The combination with a fluid heating furnace of the vertical type provided with internal flues for the products of combustion and spaces for the fluid to be heated externally bounded by the casing of the furnace and surrounding the internal flues, fuel and ashpit doors at one side and a smoke exit at the top, of an external casing spaced from the sides of the casing; a smoke outlet at the top of the external casing; a plurality of baffles dividing the space at each side of the furnace between the casings into two or more vertical flues; means for causing the products of combustion to pass through a plurality of said flues on their way to the smoke outlet or substantially directly to said outlet; and dampers whereby the extent of travel of the products of combustion through the vertical flues may be varied. 50 55

3. A fluid heating furnace constructed as set forth in claim 1 provided with other vertical baffles further dividing the space between the casings and dampers into two or more vertical flues; means for causing the products of combustion to pass through a plurality of said flues on their way to the smoke outlet or substantially directly to said outlet; and dampers whereby the extent of travel of the products of combustion through the vertical flues may be varied. 70 75

Signed at Toronto this 17th day of Oct., 80
1919.

ARTHUR J. LA FAY.
